William B. White, Nashville, Tenn., assignor to
 Marshall & Bruce Company, Nashville, Tenn.,
 a corporation of Tennessee

Application June 6, 1932, Serial No. 615,559

7 Claims. (Cl. 129—24)

This invention relates to a record binder of that type in which the cover members are removably locked to the impaling posts and concerns itself with means whereby the covers are automatically locked to the impaling posts as soon as either thereof is swung to a predetermined position without the necessity of a hunting action for aligning the pintle slide with the apertures in the impaling posts.

10 The invention comprises the novel structure and combination of parts hereinafter described and more particularly pointed out and defined in the appended claims.

In the accompanying drawing which illustrates a preferred form of this invention and in which similar reference numerals refer to similar features in the different views:

Figure 1 is a fragmentary end elevational view of a record binder with one cover thrown back-
 20 wardly and involving this invention.

Figure 2 is a fragmentary and enlarged sectional view taken through the pintle slide casing substantially upon the line II—II of Figure 1, looking in the direction of the arrow.

25 Figure 3 is an enlarged sectional view taken through the rear end of the casing for the pintle slide showing the latter in elevation.

Figure 4 is an enlarged fragmentary sectional view taken upon the line IV—IV of Figure 2.

30 In connection with this invention, there is illustrated a record binder consisting of a cover member structure comprising a back member 1 to which pintle slide casings 2 are attached. The usual cover members 3 are hinged to the back as

35 is well known in the art. Each of the casings 2 has suitable notches 4 in its forward edge for receiving the ends of impaling posts 5 which are provided with suitable apertures 6 for receiving the pintles 7 on the pintle slides 8. The 40 pintle slides 8 project beyond one end of the casing where they are provided with a right-angle finger portion 9.

In the present instance, the binder is shown with a casing and a pintle slide upon each side 45 thereof. It will, however, be understood that a single pintle slide may be used if desired. As the casings and pintle slides are substantially duplicate except that one is right-hand and the other is left-hand, only one of them need be described.

50 In referring to Figure 2, it will be noted that a spring yoke 10 is mounted within the casing and is provided with oppositely extending arms 10a. One arm 10a terminates in curved shoulder 11 which is located in a recess 8a in the pintle

slide 8 and is adapted for engaging either the shoulder 12 or the shoulder 13 in the ends of the notch or recess 8a as will later more fully appear. The other arm 10a of the spring yoke carries a rearwardly extending portion or arm 14 which is located in a recess 15 cut in the edge of the pintle slide 8. A coil spring 16 in abutting relation with the rear shoulder of the recess 15 surrounds the portion 14. The two arms 10a merge into an eyelet 17 which extends through the back of the binder and is anchored by means of a strap 18 which is fastened by a rivet 19 extending into the back of the binder.

In referring to Figure 3, it will be noted that a pin 20 extends through the casing 2 and serves as a stop for the pintle slide 8, the rear end of which is adapted to abut pin 20 when it is pushed inwardly to its full operative position. When the slide is in its full operative position, the shoulder 11 on the spring yoke will of course be no longer located in the notch 8a but will be positioned against the edge of the slide 8 at a point a short distance rearwardly of the rear shoulder of the notch 15. However, when the pin 20, which may be in the form of a screw, is removed, the slide 8 can be pushed rearwardly until the shoulder 11 on the spring yoke engages in the long notch 15 and is adapted for engaging the rear shoulder of such notch 15 for permanently locking the slide 8 from any forward movement with the result that the binder becomes permanently locked. This permanent locking feature of the binder is very desirable when the binder has been filled and it is desired to store the same away for safekeeping.

In the operation of this binder, the pintle slide 8 may be pulled outwardly by grasping the finger portion 9 until the shoulder 11 on the lock spring yoke 10 engages the rear shoulder of the notch 8a. In this position of the slide, the pintles 7 will have become entirely disengaged from the impaling posts 5 with the result that the cover and back portions of the binder can be swung into the position shown in Figure 1. However, as soon as the pintle slide is released, the spring 16 acting against the shoulder 15a of the slide will force the same rearwardly until the shoulder 11 on the lock spring yoke 10 will engage the shoulder 12 of the notch 8a. In this position of the slide, the pintles 7 will bridge a portion of the notches 4 as shown in Figure 2. The pintles 7 are inclined at the forward edges as indicated at 7a with the result that they may be automatically thrust forwardly when brought into engagement with the impaling post 5. With the pintle slide in the position shown in

Figure 2, the cover 3 and back portion of the binder may be swung to their closed position and as soon as the posts enter the notches 4, the engagement with the sloping surfaces 7a of the pintles will snap the same forwardly in order to pass the impaling posts, and as soon as the pintles 7 come into registry with the apertures 6, the spring 16 will automatically draw the pintle slide rearwardly and engage the pintles with the apertures in the post. This automatic engagement of the pintle 7 with the post 5 will of course be only partial but by manually pushing inwardly on the pintle slide 8, the pintles 7 may be brought into full engagement with the impaling posts 5.

It will be appreciated that the spring 16 when put under compression by the forward movement of the pintle slide will act automatically to push the pintle slide inwardly a predetermined extent when released by the operator. This predetermined extent to which the spring 16 may automatically operate the pintle slide is equal to the extent of the notch 8a. In other words, the pintle slide 8 may be withdrawn until the shoulder 11 strikes the shoulder 13 and when the pintle slide is released, the spring 16 will automatically push the pintle slide inwardly a distance equal to the length of the notch 8a. This distance will partially project the pintles 7a across the notches 4, whereby such pintles may be automatically engaged with the impaling posts without the necessity of any hunting action.

I am aware that many changes may be made, and numerous details of construction may be varied through a wide range without departing from the principles of this invention, and I, therefore, do not purpose limiting the patent granted hereon, otherwise than necessitated by the appended claims—

I claim as my invention:

1. In a record binder embodying a plurality of impaling posts having apertured ends, a cover member having a casing with notches for engaging said apertured ends, a pintle slide in said casing having pintles for engaging said apertured ends of said posts, means for drawing the slide outwardly a predetermined extent for disengaging said pintles from said impaling posts, and means for automatically projecting said pintles a predetermined distance inwardly when said slide is released for the purpose set forth.
2. In a record binder having a plurality of impaling posts with apertured ends, a cover member having a casing with notches for engaging said apertured ends, a slide in said casing having pintles for engaging said apertured ends, means for retracting said slide for disengaging said pintles from said apertured ends and resilient means for drawing the slide inwardly a predetermined extent when the same is released by the operator for causing said pintles to partially bridge said notches, said pintles having sloping

ends whereby said pintle slide may be automatically actuated when the pintles are brought into engagement with said impaling posts for the purpose set forth.

3. In a record binder having a plurality of impaling posts with apertured ends, a cover member having a casing with notches for engaging said apertured ends, a pintle slide in said casing for engaging said apertured ends, and yielding means for partially positioning the pintles of said slide in said notches. 80

4. In a loose leaf binder embodying a plurality of impaling posts with apertured ends, a cover member having a casing with openings for engaging said apertured ends, a slide in said casing having pintles adapted for engaging said impaling posts and resilient means for partially engaging said pintles with said posts when said casing is moved into engagement with said posts. 90

5. A record binder having a plurality of impaling posts with apertured ends, a cover member having a casing with openings for receiving said apertured ends, a slide in said casing having pintles for engaging said apertured ends, said slide having a notch of a predetermined extent, 100 a member having a shoulder engaging in said notch, said pintle slide having a shoulder spaced from said notch, a spring mounted in said casing for engaging said slide shoulder and being put under compression when said slide is pulled outwardly and effective for automatically retracting said slide approximately the distance of said notch for partially projecting the pintles across said openings. 105

6. In a record binder embodying a plurality of 110 apertured impaling posts, a cover member having a casing with notches for engaging said posts, a slide having pintles within said casing for engaging said posts, means for limiting the inward and outward movement of said slide, yielding 115 means put under compression when said slide is pulled outwardly and effective for retracting said slide a predetermined extent when released by the operator for partially projecting the pintles of said slide across said notches, said pintles 120 having bevelled ends adapted for engagement by said impaling posts for shifting said slide outwardly, said yielding means automatically pulling said slide inwardly for engaging said pintles with said apertures when the same are in registry with said pintles. 125

7. In a record binder embodying a plurality of impaling posts having apertured ends, a cover member having a casing with notches for engaging said apertured ends, a slide having pintles 130 within said casing for engaging said apertured ends, and resilient means for partially engaging said pintles with said apertured ends when said cover member is moved from open to closed position. 135

WILLIAM B. WHITE.
